CLAIM

The ornamental design for a golf ball carton, as shown and described.

DESCRIPTION

FIG. 1 is a perspective view of a golf ball carton showing my new design;

FIG. 2 is a perspective view of another embodiment of a golf ball carton;

FIG. 3 is a top plan view of FIGS. 1 and 2;

FIG. 4 is a typical side elevational view of FIG. 1; and,

FIG. 5 is a typical side elevational view of FIG. 2.

The broken line of showing golf balls is for illustrative purpose and forms no part of the claim.
